Attorney.

UNITED STATES PATENT OFFICE

ARTHUR RICHTER, OF BERBISDORF, GERMANY

JACK MOTION

Application filed April 8, 1930, Serial No. 442,630, and in Germany April 11, 1929.

The present invention relates to a jack motion in flat hosiery frames.

In flat hosiery frames such as cotton frames and the like the facing bar hitherto had to actuate also the jacks when withdrawing the sinkers and to handle their spring blocks, too, if necessary. In machines of the newer type this has already been changed and the facing bar relieved in so far as the spring blocks are removed completely from the jacks at the insertion of the facing bar which has to push back the jacks only.

According to the present invention, the facing bar is relieved also of this operation either completely or to a large extent owing to the withdrawal of the jacks by their spring blocks or other suitable adjusting means.

Several embodiments of the invention are illustrated in the accompanying drawings, in which Figure 1 is a cross section of the means required for adjusting the jacks, sinkers, facing bar, spring blocks and the like, the spring blocks being pressed against the noses of the jacks during the sinking of the loops; Fig. 2 is a view of the spring blocks engaging the noses of the jacks; and Figs. 3 and 4 are modifications of the invention.

Referring to the drawings, the sinkers 1 are horizontally displaceable in the known manner in the sinker bar 2 by means of the jacks 7 and the facing bar 9. On the jacks 7 act the slur 8 and the spring blocks 24 which engage the noses 23 of the jacks 7 rotatably supported in the usual way by their carrier bar 21. The bars 25 of the spring blocks 24 are secured to a lever 27 which rotates about the bolt 26 and the other arm 50 of which is swung to and fro by a cam 16 adapted to rotate with the main shaft 30. In this way the spring blocks 24 can be lifted off temporarily from the noses 23.

The parts described move in such a way that at the moment when the sinkers 1 are brought forward completely by the jacks 7 and the facing bar 9 is lowered to withdraw the sinkers 1, the spring blocks 24 are lifted off fully from the noses 23 of the jacks 7. For this purpose, an indentation 51 is provided on the cam 16. The jacks are then pushed back by the sinkers 1 withdrawn by

the facing bar 9 to the extent that the nose 23 lies on a lower level than the ends 52 of the springs 24, whereupon the spring blocks 24 again approach the jack noses 23 and lie above them so that they pull back the jacks 7 by their noses 23 owing to the pressure transmitted from the cam 16. Thus the facing bar is almost entirely relieved of the work of moving back the jacks.

It has happened sometimes, and especially after prolonged stops of the machine or when it was very cold, that the sinkers could not be withdrawn quickly enough by their facing bar, owing to the thickening and hardening of the lubricant, so that the loops resting on the nibs of the sinkers 1 could not slip off rapidly enough and were torn. This defect is eliminated completely by the arrangements described above.

In order to free the facing bar 9 completely from the work of moving back the jacks 7, the bolt 26 of the lever 27 need not be secured firmly to the machine frame, but can be connected to a lever 33 adapted to swing about the journal 34 on the machine frame and firmly connected with a second lever, 35, the guide roll 36 of which is moved by a cam 37 arranged on the main shaft 30. This cam is shaped so that it will move up the spring block 24 when the latter is lifted off from the nose 23 by the lever 27 and the free end of the spring 24 moves about the nose 23 and subsequently hugs the upper side of the nose 23 according to Fig. 2, the raising of the spring block 24 being caused by the indentation 53 of the cam 37. When the roll 36 of the lever 35 moves out of the drop 53, the spring block 24 is lowered again and engages the noses 23 of the jacks which are thus moved back.

It is not absolutely necessary to move back the jacks 7 exclusively by means of the spring blocks 24. This operation could be carried out also by a guide rod 40 movably arranged on the machine frame or carried by levers, according to Fig. 3, and adapted to engage an auxiliary arm 41 of each jack 7 and to depress it whenever the jacks are to be moved away from the sinkers 2, in which case the

spring blocks 24 are simply moved to and fro.

5 Simplification of the drive of the jacks is attained, if the spring blocks 24 engage a groove or notch 42 of the jacks 7. In this case the oscillatory motion of the spring blocks 24 can possibly be dispensed with completely, though it will be necessary to provide for motion in their longitudinal direction, which can be effected in various ways.

10 For example, it would be possible to arrange the lever 27 to which the bars 25 are secured longitudinally displaceably in the machine frame so that the lever 33 has to do only with the up and down motion of the lever 27.

15 When this modification is used, attention should be paid that the spring blocks 24 do not get out of the range of the groove 42 during successive adjustment of the jacks 7 by the slur 8.

20 I claim:—

25 1. A jack motion in flat hosiery frames, comprising sinkers, jacks adapted to move the said sinkers forward and spring blocks adapted to withdraw the said jacks jointly, 90 said jacks having grooved noses forming part thereof, and spring blocks adapted to engage with their ends in the said grooves and to swing, during their up and down movements, the said jacks forward and backward.

30 2. A flat hosiery frame comprising sinkers, jacks for moving the said sinkers forward and spring blocks adapted to withdraw the said jacks jointly, wherein the jacks 95 are swung backwardly from the facing bar which withdraws the sinkers, during the time that the spring blocks are entirely lifted away therefrom, only to such extent that the noses of the jacks lie at a lower level than the ends of the springs, whereupon the spring blocks again come into contact with the jacks, but at points above their noses, and thereby withdraw the same.

35 3. In a flat hosiery frame as in claim 2, 100 means whereby the spring blocks are arranged for up and down motion, in order to withdraw the jacks during their downward movement before the latter have been affected by the facing bar.

40 4. A flat hosiery frame in accordance with 105 claim 2, having means whereby the adjusting device is arranged to be movable up and down in order to withdraw the jacks by their downward movement before the latter are affected by the facing bar.

45 5. A flat hosiery frame as in claim 2, 110 wherein, after the jacks have completely brought the sinkers forward, the spring blocks are moved upwardly in such way that the spring ends thereof will be positioned 115 above the noses of the jacks, so that upon their downward movement, which then follows, they will draw back the jacks.

60 6. A flat hosiery frame as in claim 2, 120 wherein the noses of the jacks are provided 125

with notches into which engage the ends of the springs, so that upon an upward movement of the latter the jacks will be swung forward and upon a downward movement they will be swung backward.

70 In testimony whereof, I have affixed my signature.

ARTHUR RICHTER.
